ATTORNEY

UNITED STATES PATENT OFFICE.

CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE.

HEAD FOR SHIPPING DRUMS.

Application filed April 16, 1927. Serial No. 184,256.

This invention relates broadly to metallic shipping drums, and more specifically to a head and removable cover for such drums.

The primary object of the invention is to provide a sheet metal barrel or drum-like container of a type commonly employed for one-time use in shipping heavy material, as powdered calcium carbide, the same having a head and slip cover construction adapted to withstand the usual shocks and jars incident to rough handling without rupture at the joints and without danger of the cover becoming so dislodged or unseated as to permit leakage, or shifting, of the contents of the barrel.

A further object is to provide a head and cover structure of the character mentioned embodying means whereby much of the force of shocks to which it is subjected is effectually absorbed without injury to the joints.

In describing the invention in detail, reference is herein had to the accompanying drawings, in which—

Figure 1 is a head-end elevation of a drum embodying my invention;

Figure 2 is a section on line 2—2, Fig. 1; and—

Figure 3 is an enlarged detail section on line 3—3, Fig. 1.

Referring to said drawings, 1 designates the body of a drum or barrel-like container of the general character employed in making one-time shipments of materials and ordinarily made of light-gauge sheet metal.

Attached to one end of the body 1 in any appropriate manner, as by the lock-seam 2 shown in the drawings, is a sheet metal head 3 having therein a central opening designed for the reception of a removable closure 4 of the slip-cover type, said opening being defined by an upwardly extending flange 5 which is designed to receive the closure 4 in snugly seated relation thereto.

The flange 5 is constituted by an extension of the inner wall of a downwardly pressed circular bead 6 formed in the head 3. The outer wall of said bead 6 meets and forms with the inner wall of an upwardly pressed bead 7 a compound curvature for affording relatively great resilience so that the structure is readily yieldable for absorbing shocks which may be imposed upon the head in handling of the container.

The upper edge portion 5^a of the flange 5 is turned outwardly into partially overhanging relation to the upwardly facing channel which is formed by the provision of the bead 6, thereby forming a seat for the reception of a gasket 8.

The closure or cover 4 has an upright annular wall 9 which seats snugly within the embrace of the head flange 5 and which has its upper edge portion or extremity curved outward to form a roll-like terminal 9^a for seating upon the seated gasket 8. Tongues 10 are formed at suitably spaced intervals on the edge 5^a of the flange 5, the same being adapted to be bent inward into seated relation to the terminal roll 9^a for securing the cover in its properly seated position in compressing relation to the interposed gasket.

Formed in the head 3 directly adjacent to the seam 2 is an upwardly pressed bead 11 which is designed to render the head yieldable relative to the seam under shocks to which the container is subjected, thereby to reduce the liability of the container to rupture at or adjacent to said seam.

It will be noted that the tongues 10 effectually maintain the cover 4 against displacement from its seated position wherein the terminal roll thereof acts to compress the gasket into sealing relation to the joint between said cover and the head 3. Moreover, it will be apparent that the flange 5 and the therewith associated double, or reverse, bead formation of the head provide an especially resilient construction adapted to absorb impacts or shocks incident to forcible shifting of the contents of the drum against the head and cover which would otherwise tend either to rupture the head or to so distort the latter as to permit leakage at the joint.

What is claimed is—

1. A sheet metal container having a head formed with a central circular opening defined by an upstanding flange, said head having therein a downwardly pressed bead of which the inner wall is extended to form said flange, said head also having therein an upwardly pressed bead of which the inner wall meets and forms with the outer wall of the first mentioned bead a compound curvature, a slip cover for seating within the em-

- brace of said flange, and tongues formed on said flange for bending inwardly into retaining relation to said cover.
2. A sheet metal container having a head 5 formed with a central circular opening defined by an upstanding flange, said head having therein a downwardly pressed bead of which the inner wall is extended to form said flange, said flange having its terminal 10 edge portion turned outwardly into overhanging relation to said bead to form a seat for a gasket, said head also having therein an upwardly pressed bead disposed in closely encircling relation to the downwardly 15 pressed bead, a slip cover having an upright annular flange for seating within the embrace of said head flange and provided with a terminal edge portion turned outwardly into overhanging relation to said gasket 20 seat, and tongues formed on said head flange adapted to be turned inwardly into seated relation to said terminal edge portion of the cover flange, the reversely disposed beads 25 cooperating to render that portion of the head adjacent to the cover readily resilient for absorbing impacts and preventing rupture of the joint between the head flange and the cover.
3. A sheet metal container comprising a body, a head attached peripherally to said body and having therein a central circular opening, an upstanding flange defining said opening and having its terminal edge portion inclined outward to form a gasket seat, 30 tongues borne by said edge portion at spaced intervals, said head having therein a downwardly pressed circular bead and a closely adjacent encircling upwardly pressed bead, the inner wall of the downwardly pressed 35 bead having said flange formed as a continuation thereof, and the adjacent walls of said beads combining to form a compound curvature, and a removable slip cover fitted within said opening, said cover having an upright flange received snugly within the 40 embrace of said head flange and terminating in an outwardly turned portion which 45 overhangs said gasket seat, said tongues being adapted for turning into seated relation to said outwardly turned portion of the 50 cover flange.
4. A sheet metal container comprising a body, a head attached to said body through the provision of a seam, said head having an upwardly pressed bead formed therein 55 closely adjacent to said seam, said head being provided with a circular opening defined by an upstanding flange and having therein a downwardly pressed bead of which the inner wall is extended to form said 60 flange, said flange having its terminal edge portion inclined outwardly to form a seat for a gasket, a slip cover having an upright annular flange fitted within the embrace of 65 said head flange and provided with a terminal portion which overhangs said seat for resting upon a gasket supported by the latter, and means whereby said cover is secured in its seated closing position.
5. A sheet metal container comprising a body, a head attached to said body through the provision of a seam, said head having an upwardly pressed bead formed therein 70 closely adjacent to said seam, said head being provided with a circular opening defined by an upstanding flange and having therein a downwardly pressed bead of which the inner wall is extended to form said flange, said flange having its terminal edge portion inclined outwardly to form a seat 75 for a gasket, a slip cover having an upright annular flange fitted within the embrace of said head flange and provided with a terminal portion which overhangs said seat for resting upon a gasket borne by said seat, 80 and a plurality of tongues formed upon said 85 terminal edge portion of the head flange and adapted for turning into overlying seated relation to the terminal portion of said cover flange.
- In testimony whereof, I affix my signature.

CHARLES H. ROLLASON
